UNITED STATES PATENT OFFICE.

WALTER LIGHT BODMAN, OF NEW YORK, N. Y., ASSIGNOR TO THE INSULATION CORPORATION, A CORPORATION OF DELAWARE.

TIMING MECHANISM.

Application filed December 10, 1925. Serial No. 74,477.

My invention relates to improvements in timing mechanisms such as are adapted for use in controlling various operations, as for instance the opening and closing of a valve, 5 the opening and closing of an electric circuit, or do other work at predetermined intervals of time.

My invention is intended to provide means whereby the standard or conventional time-piece, as for instance a clock mechanism, preferably one having primary and secondary springs as for example, an alarm clock, can be made to do work at stated periods of time and to work automatically. My invention is 10 further intended to provide means whereby one part of the time-piece or clock-work will actually perform the work to be done by moving a lever and the other part or timing portion of the clock-work will act to reset the 15 operating mechanism.

My invention is further intended to adapt a timepiece for the purposes stated and in such a manner that the operating element can be moved at regular intervals throughout the 20 day and night, or can be made to operate at more frequent intervals for one part of the day or can be held inoperative for a substantial period, all of which can be regulated as desired. This will be better understood from 25 the description which follows.

Reference is to be had to the accompanying drawings in which similar reference characters represent corresponding parts in all the views.

30 Figure 1 is a side elevation of clock-work showing my improvement.

Figure 2 is a front elevation thereof.

Figure 3 is a side elevation from the opposite side from that shown in Figure 1.

40 Figure 4 is a broken front elevation with parts removed.

Figure 5 is a plan view of the apparatus.

Figure 6 is a diagrammatic perspective of the locking and resetting mechanism.

45 Figure 7 is an enlarged detailed cross section of a crown wheel forming part of the invention, the section being taken on the line 7-7 of Figure 8.

Figure 8 is a face view of the crown wheel.

50 In carrying out my invention any time-piece adapted to keep time and preferably one having two spring barrels such as an alarm clock can be used, and in the drawings 10 represents a suitable frame for supporting the mechanism and this, of course, may be of

any improved design. I have shown the apparatus provided with a spring barrel 11 for the alarm side of the mechanism and a spring barrel 12 for the timing gears. The springs and gears for the alarm and also for the timing part are not shown in detail for these will vary with different clock-works, and the gearing itself is not important as my apparatus can be applied to any clock-work of the kind referred to.

Referring to Figure 4 it will be noted that the spring barrel 11 carries cams 13 which are faced on a cam wheel 13' and these, when the cam wheel turns impelled by the spring barrel, contact with a wheel 14 on a lever 15 which is pivoted at one end as shown at 16 and provided with an abutment 17 which in turn may contact with some part to be operated. As illustrated in the present case this abutment 17 is adapted to hold an expansion valve closed as illustrated in my application for Letters Patent of the United States for an improvement in refrigeration system and method, filed November 21st, 1925, Serial No. 70,506, but so far as my present invention is concerned the lever 15, or corresponding part, may do any work within the power of the spring barrel 11, and it will be readily seen that the part moved by the cams 13 may do a great variety of work. It will also be understood that these cams 13 can be spaced at regular or irregular intervals without affecting the invention.

In the drawings I have shown the alarm side of the clock-work provided with a conventional escapement 18 adapted, when locked, to lock the spring barrel 11 and connected parts and the pawl of the escapement is carried by an arbor 19 as usual, but the arbor is provided with a crank 20 which is not usual and which extends upwardly as shown in Figure 6. This is normally engaged by a hook 21 on the arm or rod 22 which has its opposite end bent inwardly as at 23 and is fastened to a slide rod 24 which is pressed by a spring 25 and which is adapted to move inward across the supporting frame of the clock-work. This movement is effected primarily by a spring arm 26 which is pivoted at one end as shown at 27 and has a bent end 28 which serves as a pawl, as presently described, and has on the under edge a notch 29 to permit it to set over the main arbor, which will presently be referred to. The free end of the spring arm 26 carries a coil 30 in the form

of an extension and this rides on the weighted arm 31 of an arbor 32 which is pivoted in the frame of the clock-work parallel with the rod 24. The arbor 32 has a crank 33 pivotally connected with a forwardly extending bent link 34 this having at its end a head 35 with a shoulder 36 thereon. The shoulder 36 is adapted to drop over and engage the angle bracket 37 on the upper end of the lever 15. 10 This bracket is preferably adjustable up and down on the lever and to this end is provided with a bolt 38 extending through a slot 39 in the upper part of the lever 15.

The movement of the parts above described 15 is controlled by the teeth 40 of the crown wheel 41. These teeth are arranged in a flange of the crown wheel and are pitched one way with a broad shoulder the other way like ordinary ratchet teeth. The crown wheel has 20 a pinion 42 rigidly attached thereto and this is geared to the time train of the clock so that the crown wheel 41 moves regularly, and as a matter of fact, it is attached to an arbor which would otherwise carry the cannon 25 pinion of the clock, and therefore the crown wheel turns at the same rate as would the hour hand of the clock, if a hand were used. These teeth control the operation of the cams 13 as to the time and as to the length of the 30 periods at which the cams operate. Therefore it will be seen that the spacing of the teeth or the length of them will regulate these movements. For example, if the cams were to operate every thirty minutes for a twenty- 35 four hour period, there would be forty-eight evenly spaced teeth 40, but if it is desired to have the operations at 30 minute periods for a part of the day and at other periods for the rest of the day, obviously the teeth would be 40 correspondingly arranged. That is, the teeth would be longer or spaced further apart where the operations would be less frequent, and shorter or nearer together when the operations are to be more frequent.

The crown wheel 41 carries a dial 43 which 45 can be marked off in a manner corresponding to a clock dial, but preferably with the twenty-four hours indicated in two series of one to twelve each. On the periphery of the wheel 41 are cycloidal teeth 44 spaced according 50 to the hour periods and the curved recesses between the teeth are adapted to receive a weighted roller 45 which is carried on a tilting lever 46, this being pivoted as at 47 on a part of the main frame. The lever 46 has one end extending beneath the link 34 so that at proper periods it may lift the link 55 for the purpose which will now be described.

In the drawings it is assumed that when 60 a cam 13 is turned out of contact with a roller 14 the lever 15 will move inward and perform some work, as for example, the opening of a valve or the closing of a circuit and will continue to do this until it is again moved out 65 by one of the cams 13, and it is further as-

sumed that when a cam and a lever are in the position shown in Figure 4 the parts are locked and no work is being done. But as the crown wheel 41 moves at its regular rate one of the teeth 40 contacting against the 70 spring arm 26 moves the spring arm inward, thus pushing in the rod 24 and arm 22 and freeing the hook 21 from the crank arm 20 (see Figure 6). This permits the secondary part of the time piece or clock-work that 75 is the part impelled by the spring barrel 11 to start and the cam 13 turns out of contact with the roller 14 permitting the lever to move and do its work. As the lever moves in the head 35 drops over the bracket 37 and 80 locks the parts temporarily in the position assumed, but as the alarm arbor continues to move the cam will again strike the wheel 14 moving the lever forward pulling on the link 34 and moving the crank 33, arbor 32, 85 arm 31 and arm 36 back to the original position while the weighted roller 45 dropping between the cycloidal teeth 44 will tilt the lever 46 and lift the link 34, thus permitting the arm 31 to drop back, pulling with it the 90 head 35 and restoring the parts to the position at the beginning of the cycle of operations.

From the foregoing description it will be 95 seen that any timepiece or clock-work having primary and secondary springs, that is alarm and timing springs, can be made to do any work within the limits of power of the primary or alarm spring, that the intervals are controlled by the timing mechanism and that this may be adjusted by regulating the teeth 100 40 so that the above described cycle of operations will take place at such intervals or periods as may be desired, and that by reason of the timing mechanism and the spacing of the cams 13, the operations may be made more or less frequent.

I claim:

1. A timing mechanism comprising a time-piece having a primary driving spring, a lever moved by said spring, a lock for the spring, a secondary spring driving the time train, means in the time train for repeatedly releasing the lock, means connected with the lever for resetting the lock after each release, and time controlled means for breaking the said lever connection. 110

2. A timing mechanism comprising a time-piece having a primary driving spring and secondary driving spring actuating separate gear trains, means for transmitting motion from the primary gear train to an external part, a rotary toothed wheel driven by the secondary gear train having one set of teeth spaced to represent hours and a second set spaced to represent shorter intervals, and means actuated by the individual teeth of both sets for releasing and locking the primary gear train. 120

3. A timing mechanism comprising a time- 130

piece having a primary driving spring operating a gear train, a secondary timing spring operating a second gear train, a wheel actuated by the secondary gear train having teeth spaced to represent intervals of time and a second set of teeth spaced to represent shorter time intervals, and means operated by the individual teeth of both sets to control the primary gear train.

- 5 10 4. A timing mechanism comprising a primary spring driven gear train which is normally locked, a secondary and separate spring driven gear train, a wheel driven by the secondary gear train having spaced teeth and separate spaced recesses, means actuated by the teeth to periodically release the primary gear train, and means operated by engaging the recesses to assist in resetting the lock.
- 15 20 5. A timing mechanism comprising a time-piece having a primary spring driven gear train which is normally locked, a member moved by said gear train, a separate secondary spring driven gear train, a means oper-

ated by the secondary gear train for releasing the lock, a link connecting the secondary gear train with the movable member to assist in resetting the lock, and means operated by the secondary gear train for releasing the link from the movable member.

6. A timing mechanism comprising a time-piece having a primary normally locked spring driven gear train, a member moved by said train, a secondary separate spring driven gear train, a crown wheel having spaced teeth on the side and also peripheral recesses, a link connecting the secondary gear train with the movable member, means operated by the crown wheel teeth to release the primary gear train, and a tilting lever operated by the recessed part of the crown wheel and disposed to release the link from the movable member.

In testimony whereof, I have signed my name to this specification this 20th day of November, 1925.

WALTER LIGHT BODMAN.
